AUTOMATIC PARKING METER

Gerald A. Hale, Oklahoma City, Okla.

Application August 3, 1950, Serial No. 177,429

17 Claims. (Cl. 194—72)

1

This invention relates to an automatic parking meter for indicating the parking time on city streets, and analogous places.

The present invention contemplates an automatic self-winding type parking meter which is wound and placed in operation by the force of the operator's finger through the medium of the coin inserted in the coin slot. The force exerted upon the coin is utilized to operate an actuating mechanism in turn winding the clock works of the meter, and moving a coin rotator into coin receiving position. The coin is moved through the meter by the spring loaded coin rotator to actuate the resetting mechanism. The time indicator is momentarily released by the resetting mechanism to return to a starting position under the energy of a spring, such starting position being regulated by a stop mechanism cooperating with the resetting mechanism. The movement of the resetting mechanism, and the stopping position of the stop mechanism is dependent upon the denomination of the coin inserted in the meter, in order that the parking time obtained will vary according to the denomination of the coin. The time indicator is connected to a gear train of a time means; however, upon operation of the reset mechanism, the indicator is momentarily disengaged from the clock train to allow resetting thereof to a predetermined starting position. After resetting, the indicator is re-engaged with the clock train to cooperate with the clock in determining the parking time utilized.

It is also contemplated to provide a parking meter wherein the actuating mechanism is locked in such a position to close the coin slot during operation of the resetting mechanism. In this manner, a second coin of required denomination cannot be inserted in the coin slot to jam the reset and indicating mechanism in such a position that parking time would be indicated as available. The closed coin slot also prevents anyone from "fishing" a coin previously inserted in the meter. In addition, the resetting mechanism is locked when the actuating mechanism is moved away from the coin slot, thereby preventing tripping of the reset mechanism except by the insertion of a coin in the meter.

An important object of this invention is to provide a fully automatic parking meter wherein the clock works of the meter are wound by the force of the operator's fingers through the insertion of a coin in the meter.

A further object of this invention is to provide a parking meter which is operable on more

than one denomination of coins as well as multiple coins of each of the denominations.

Another object of this invention is to provide a parking meter wherein the extent of winding of the clock works upon the insertion of a coin in the meter may be varied as desired.

Another object of this invention is to provide a parking meter wherein a coin inserted in the meter is moved through the meter by the energy of a spring to actuate the resetting and indicating mechanisms.

An additional object of this invention is to provide a parking meter which cannot be jammed by the successive insertion of two or more coins.

15 A still further object of this invention is to provide a parking meter wherein the coin slot is closed during operation of the reset mechanism.

20 A further object of this invention is to provide a parking meter wherein the reset mechanism is locked in an inoperative position as long as the coin slot is open.

Another object of this invention is to provide a parking meter readily adapted for use with 25 a similar meter in a single meter housing to provide a twin meter.

And an additional object of this invention is to provide a parking meter which is fully automatic, durable and simple in construction to facilitate the maintenance and adjustment thereof.

Other objects and advantages of the invention will be evident from the following detailed description, read in conjunction with the accompanying drawings, which illustrate my invention.

In the drawings:

Figure 1 is a front elevational view of the meter with the front half of the housing removed illustrating the meter when the parking time has expired, with portions of the meter shown in dotted lines to illustrate part of the operation.

40 Figure 2 is a view similar to Figure 1 illustrating the meter in operation.

Figure 3 is a vertical sectional view taken essentially on lines 3—3 of Figure 1.

45 Figure 4 is a detail view illustrating the relationship of the rear actuating lever and the main spring barrel.

Figure 5 is a view similar to Figure 4 showing the positions assumed by the rear actuating lever and main spring barrel upon the insertion of a coin in the meter.

50 Figure 6 is a detail illustrating the relationship

of the front actuating lever and the coin rotator.

Figure 7 is a view similar to Figure 6 showing the parts in operation.

Figure 8 is a detail illustrating the relationship of the front actuating lever and the reset lever.

Figure 9 is a view similar to Figure 8 illustrating the parts in one operation.

Figure 10 is a view also similar to Figure 8 illustrating a second operation of the parts.

Figure 11 is a detail of the warning flag actuating mechanism in non-operating position.

Figure 12 is a view similar to Figure 11 illustrating the mechanism in operation.

Referring to the drawings in detail and particularly Figures 1, 2 and 3, reference character 14 designates a novel parking meter mechanism generally. The parking meter mechanism 14 is disposed in a sectional housing 15 having a hinged connection permitting opening thereof. A coin inlet slot 16 is provided in one side thereof and a coin discharge slot 17 in the lower portion thereof. An arcuate shoulder 18 is provided above the coin slot 16, and a shoulder 19 is provided below the coin slot 16 for purposes as will be herein-after set forth. An arcuately shaped coin chute 20 is provided in the housing 15 and extends from below the coin slot 16 to a point slightly above the coin discharge slot 17. The coin chute 20 is essentially L-shaped in cross section and has an arcuate slot 21 in the vertical leg thereof. A suitable coin stop 22 is provided in spaced relation to the lower end 23 of the coin chute 20.

The meter 14 comprises a pair of stationary (Fig. 3) front and rear plates 24 and 25 respectively, interconnected by a plurality of bolts (not shown). The rear plate 25 is suitably secured (not shown) to the housing 15. A time-indicating dial 26, having appropriate time markings 27 thereon, is secured to the upper end of the front plate 24 by screws 28.

As clearly shown in Figure 3, a main shaft 29 extends through the rear plate 25 and is journaled in the front plate 24. The outer end 30 of the main shaft 29 is adapted to receive a winding handle (not shown) as will be herein-after set forth. A main spring barrel 31 is rigidly secured to the outer end 30 of shaft 29, adjacent the rear plate 25. A main spring 32 is disposed in the spring barrel 31 and has its outer end 33 frictionally connected to the spring barrel 31 in the usual manner. The inner end 34 of the main spring 32 is secured by a clip 35 to the hub 36 of a main time gear 37. The hub 36 is rotatably disposed on the main shaft 29 and extends into the main spring barrel 31 as shown in Figure 3. The main time gear 37 meshes with a pinion 38 provided on a shaft 39 for interconnecting to a timer or escapement 40.

From the foregoing, it is apparent that the main spring barrel 31 is utilized to wind the main spring 32 upon rotation of the main shaft 29 and barrel 31. The main spring 32, through the medium of the clip 35 and hub 36, drives the main time gear 37. The speed of rotation of the main time gear 37 is regulated and controlled by the timer 40 through the medium of the pinion 38 and shaft 39.

Referring to Figs. 1 and 2, an arcuate closure element 41, hereinafter termed a "duck-bill" because of its shape, is normally disposed in the coin inlet slot 16. The duck-bill 41 is pivotally carried on a pin 42 between the front and rear actuating levers 43 and 44 respectively (Figs. 4 and 6). An extension 45 is provided on the upper

end of the duck-bill 41 adjacent a horizontally disposed stop pin 46, also secured in the front and rear actuating levers 43 and 44. The stop pin 46 is disposed on the outer side of the extension 45, thereby precluding the duck-bill 41 from pivoting counter-clockwise on the pin 42. The duck-bill 41 may, however, be pivoted clockwise as will be hereinafter set forth. The front actuating lever 43 (Fig. 6) is pivotally disposed on a pin 47 secured in the stationary front plate 24. The rear actuating lever 44 (Fig. 4) is pivotally disposed on a pin 48 secured in the stationary rear plate 25, in aligned relationship (not shown) with the pin 47. It is, therefore, apparent that the actuating mechanism, comprising levers 43 and 44 and duck-bill 41, may be pivoted as a unit about a horizontal axis extending through the pivot pins 47 and 48.

The rearwardly disposed actuating levers 43 (Fig. 4) is provided with a plurality of apertures 49 spaced at varying distances from the pivot pin 48. A winding pawl 50 is pivotally secured by a pin 51 in one of the apertures 49. The pawl 50 engages gear teeth 52 provided on the outer periphery of the main spring barrel housing 31 to rotate the barrel 31 when the rear actuating lever 44 is rotated in a clockwise direction (Fig. 4) on the pin 48. The degree of rotation of the main spring barrel 31, upon a predetermined degree of rotation of the lever 44, may be varied as desired by selectively securing the pawl 50 in a desired aperture 49. A suitable stop pawl 53 is disposed essentially diametrically opposite the winding pawl 50 to preclude counter-clockwise rotation of the barrel 31. The pawl 53 is pivotally carried on a pin 54 secured (not shown) in the stationary rear plate 25. A leaf spring 55 is anchored by a pin 56 secured (not shown) to the rear plate 25. The spring 55 constantly urges the pawl 53 into engagement with the teeth 52.

A cam surface 57 (Fig. 6) is provided on the upper rear portion of the front actuating lever 43, and is adapted to contact a push pin 58 of a coin rotator 59. The coin rotator 59 (see also Fig. 3) is essentially circular shaped and is rotatably disposed on the main shaft 29. A slotted extension 60, having its topmost end 61 enclosed, is provided on the periphery of the coin rotator 59 for purposes as will be herein-after set forth. An L-shaped pawl 62 (Fig. 6) is pivotally secured on a pin 63 on the side of the coin rotator 59 adjacent the front actuating lever 43. A shoulder 64 is provided on the lower leg 62a of the pawl 62 adjacent the lower end thereof. The shoulder 64 is adapted to engage a lock pin 65 carried by the lever 43 when the rotator 59 and lever 43 are in one position (Fig. 7). The upper leg 62b of the pawl 62 is normally retained in contact with the push pin 58 by the action of a suitable leaf spring 66 anchored by a pin 67 to the coin rotator 59. A suitable coil spring 68 connected to the pin 67 is anchored (not shown) to the front plate 24 and constantly tends to rotate the coin rotator 59 in a counter-clockwise direction (Figs. 6 and 7).

As shown in Fig. 1, a coin 69 being inserted in the coin slot 16 will contact the outer curved surface or face 70 of the duck-bill 41, and since the duck-bill 41 is prevented from being rotated counter-clockwise by the stop pin 46, the force of the operator's fingers, through the medium of the coin 69, will move the duck-bill 41 upwardly and clockwise (Figs. 1, 6 and 7) to pivot the actuating levers 43 and 44. The diameter of the coin 69 obviously determines the height to

which the duck-bill 41 is moved, and hence the degree of rotation of the levers 43 and 44. Since the winding pawl 50 (Fig. 4) is moved simultaneously with the actuating lever 44 to rotate the spring barrel 31, the degree of rotation of the barrel 31 and hence the extent of winding of the main spring 32 is dependent upon the size of the coin 69.

It will be apparent, however, that the difference in the extent to which the main spring 32 is wound for the various denominations of coins used, usually pennies and nickels, will be relatively small. With the winding pawl 50 secured to the lever 44 in the position shown in Figs. 4 and 5, a penny inserted in the meter 14 will cause the main spring 32 to be wound more than is necessary for the parking time obtained, as will be hereinafter set forth, and a nickel inserted in the meter 14 will cause the main spring 32 to be wound less than is necessary for the parking time obtained. In the usual parking meter installation, however, the various vehicle owners will insert a plurality of both pennies and nickels in the parking meter. Therefore, over a period of time, the main spring 32 will be maintained under sufficient tension by the insertion of pennies to assure operation of the meter 14 for one hour as will be hereinafter set forth, when a nickel is inserted therein. As previously set forth, the position of the winding pawl 50 may be varied to vary the extent of winding the main spring 32, according to the application of the meter 14. In addition, the spring 32 may be periodically wound by turning the main shaft 29 with a winding handle (not shown) to further assure sufficient tension being maintained in the spring 32 for the continued operation of the meter 14.

As the front actuating lever 43 is rotated clockwise to the position shown in Fig. 7, the cam portion 57 will co-act with the push pin 58 to simultaneously rotate the coin rotator 59 and pawl 62 in a clockwise direction. It is to be noted that the pivotal radius of the pawl 62 (the distance from any point on the pawl 62 to the main shaft 29) is greater than the pivotal radius of the lock pin 65 (the distance between the pin 65 and the pin 47). Therefore, as the pawl 62 and lock pin 65 are simultaneously rotated in a clockwise direction, the pawl 62 will come into contact with and move over the pin 65 to slightly compress the leaf spring 66. When the coin rotator 59 reaches its uppermost position, as shown in Fig. 7, the shoulder 64 on the pawl 62 engages the lock pin 65. The tension induced in the spring 68 is thereby transmitted through the medium of the coin rotator 59, pawl 62, and the lock pin 65 to the actuating lever 43 and duck-bill 41. The slotted extension 60 of the rotator 59, will then be in coin receiving position as shown in dotted lines in Fig. 1 and opposite the coin slot 16.

As the coin 69 is moved further into the coin slot 16 so that the vertical center line (not shown) thereof passes inside the lower end 72 of the duck-bill 41, the duck-bill 41 will be free to pivot clockwise. The force of the spring 68 will then cause the lower end 72 of the duck-bill 41 to jump to the outer or trailing edge of the coin 69 into contact with the arcuate shoulder 18 (Fig. 1) and force the coin on into the slotted extension 60. As the duck-bill 41 is released by the coin 69, the front actuating lever 43 and coin rotator 59 are caused to rotate counter-clockwise.

As previously noted, the pivotal radius of pawl 75 the insertion of a fresh coin or the like, which

62 (Fig. 6) is greater than the pivotal radius of the lock pin 65. Therefore, during the first few degrees of counter-clockwise rotation of the rotator 59, the duck-bill 41 will be moved to provide a closed position of the coin slot 16 as shown in Figs. 1 and 6; whereas, the coin rotator 59 moves only a few degrees. As soon as the lower end 72 of the duck-bill 41 contacts the shoulder 19 in the housing 15, the pawl spring 66 will be compressed, permitting the shoulder 64 to be disengaged from the lock pin 65. The coin rotator 59 is then allowed to continue rotating in a counter-clockwise direction to carry the coin 69 downwardly as will be hereinafter set forth.

The reset lever 73 (Fig. 1) is rotatably secured by a pin 74 to the stationary front plate 24 in downwardly spaced relation to the main shaft 29. One arm 75 of the reset lever 73 is normally disposed in essentially a horizontal position and extends to a point slightly below the coin inlet slot 16. An actuating pin 76 is secured to the outer end of the arm 75 and extends transversely to the front plate 24 into the slot 21 of the coin chute 20. A sector 77 is secured to the lower side of the arm 75 and extends to a point directly above the coin discharge slot 17. The lower end 78 of the sector 77 is adapted to contact the actuating pin 79 of a detent 80. The detent 80 is pivotally secured by a pin 81 to the front plate 24 and has a portion 82 (see also Fig. 3) of its lower end bent inwardly. The portion 82 is adapted to move into an arcuate slot 83 provided in the front plate 24 when the detent 80 is rotated in a clockwise direction.

A suitable spring 84 is anchored at 85 to the front plate 24 and is connected by a pin 86 to the reset lever 73 and constantly tends to rotate the reset lever 73 in a clockwise direction (Fig. 1). The pivot pin 47 of the front actuating lever 43 acts as a stop (Fig. 1) for the reset lever 73. A lock pin 87 (Figs. 1 and 8) is secured to the upper end of the reset lever 73 and extends through an arcuate slot 88 provided in the front plate 24 into proximity with the front actuating lever 43. A slot 89 (Fig. 8) is provided in the actuating lever 43 to receive the pin 87 upon rotation of the lever 43, as will be hereinafter set forth. The slot 89 is formed on the arc of a circle (not shown) having its center line in the actuating lever pivot pin 47. A cam surface 90 is provided on the rear edge of the actuating lever 43 slightly below the slot 89. The cam surface 90 is formed on the arc of a circle (not shown) having its center line in the reset lever pivot pin 74 when the lever 43 is in the position shown in Fig. 8.

When the actuating lever 43 is in the position shown in Fig. 8, it will be apparent that the duck-bill or closure member 41 is disposed in the coin slot 16, as shown in Figs. 1, 8 and 9, and the reset lever 73 is rotated counter-clockwise to the position shown in Fig. 9, the lock pin 87 will move into contact with the cam surface 90 and preclude clockwise rotation of the actuating lever 43. Conversely, when the reset lever 73 is in the position shown in Figs. 1, 8 and 10, and the front actuating lever 43 is moved in a clockwise direction to the position shown in Fig. 10 (as when a coin is inserted in the slot 16), the slot 89 will move over the lock pin 87 and preclude counter-clockwise rotation of the reset lever 73. Thus when the reset lever 73 is in a down position, as will hereinafter be set forth, the duck-bill 41 will be locked in the coin slot 16 to preclude

would jam the reset lever 73. Also, when the duck-bill 41 is moved upwardly, the reset lever 73 will be locked in an up position to preclude the mischievous tripping thereof and the consequent resetting of the meter.

As shown in Fig. 1, the reset lever actuating pin 76 is disposed in the path of the coin 69 when the coin is moved downwardly by the coin rotator 59. However, the slotted extension 68 is so positioned on the periphery of the coin rotator 59 that the upper end 61 thereof does not come into contact with the coin 69 until the duck-bill 41 has closed the coin slot 16 and the reset lever 73 is unlocked. As soon as the reset lever 73 is unlocked from the front actuating lever 43, the 15 coin 69 contacts the reset lever actuating pin 76 and rotates the reset lever 73 counter-clockwise. As previously noted, the pivot point 74 of the reset lever 73 is below the pivot shaft 29 of the coin rotator 59. Therefore, as the reset lever 73 and coin rotator 59 are simultaneously rotated in a counter-clockwise direction, the pin 76 moves outwardly with respect to the periphery of the coin rotator 59. The coin 69 will continue rotating the reset lever 73 counter-clockwise through 25 the medium of the actuating pin 76 until the distance between the pin 76 and the periphery of the coin rotator 59 is slightly greater than the diameter of the coin 69. The actuating pin 76 will then be released, permitting the spring 84 to reverse the movement of the reset lever 73 in a clockwise direction until the arm 75 contacts the pin 47. The coin 69 will be moved on downwardly along the coin chute 23 by the action of the coin rotator 59. It is thus readily seen that the diameter of the coin inserted in the meter determines the extent to which the reset lever 73 is moved.

Simultaneous with the counter-clockwise movement of the reset lever 73, the lower end 78 of the curved sector 77 coacts with the actuating pin 79 to rotate the detent 80 clockwise, moving the lower end 82 thereof into the slot 83. A coin (not shown) previously resting on the lower end 82 of the detent 80 and against the coin stop 22 is thereby permitted to fall by gravity through the coin discharge slot 17 into a suitable coin box (not shown). When the reset lever 73 is rotated clockwise, the detent 80 is released and permitted to move counter-clockwise back to the position as shown in Fig. 1.

A link 91 (Fig. 1) is pivotally connected by a pin 92 to the upper portion of the reset lever 73. The lever 91 is connected at its upper end to one end of a cluster shaft 93 (Figs. 1 and 3). The cluster shaft 93 extends through an enlarged aperture 94 in the front plate 24 and is supported at its opposite end by a supporting lever 95 connected (not shown) to the rear stationary plate 25 by a pin 96. A cluster spool 97 is rotatably disposed on the cluster shaft 93 between the front and rear plates 24 and 25. A time gear 98 is secured on one end of the spool 97 and is adapted to engage the main time gear 37, as shown in Figure 3. A ratchet gear 99 is secured on the opposite end of the spool 97 and has a suitable indicator 100 secured thereto. A spring 101 is anchored to the front plate 24 and connected at its opposite end (not shown) to the ratchet gear 99, and constantly tends to rotate the gears 98 and 99 in a clockwise direction (Figs. 1 and 2). A ratchet 102 is rotatably disposed on the cluster shaft 93 adjacent the outer face of the front plate 24. The ratchet 102 comprises a yoke having an upper arm 103 and a lower arm 104

105 as will be hereinafter set forth.

A spring 107 is anchored at 108 to the front plate 24 and connected at its opposite end to the pawl 105, and constantly tends to retain the pawl 105 into engagement with the ratchet gear 99 to cause rotation of the ratchet 102 in a counter-clockwise direction. The lower arm 104 has its outer end bent inwardly above the plate 24 to act as a stop for the ratchet 102. A small tooth 109 (the penny tooth) and a larger tooth 110 (the nickel tooth) are provided in circumferentially spaced relation on the ratchet 102. The teeth 109 and 110 are adapted to engage a stop pawl 111 rotatably pinned at 112 to the front plate 24. The outer end 113 of the pawl 111 is counterweighted to retain the working end of the pawl in the path of the teeth 109 and 110 as will be hereinafter set forth.

When the reset lever 73 is rotated counter-clockwise by the coin 69, as previously set forth, the reset lever 73 through the medium of the pin 92 and link 91 raises the reset cluster shaft 93. It will be noted that the supporting lever 95 on the opposite end of the shaft 93 will pivot about the pin 96 (Fig. 11) to permit the upward movement of the shaft 93 within the enlarged aperture 94. During the initial upward movement of the shaft 93, the ratchet pawl 105 engages the teeth 109 on the ratchet gear 99 to lock the ratchet 102 to the cluster gear assembly comprising gears 98 and 99. The cluster time gear 98 is then completely disengaged from the main time gear 37, permitting the indicator spring 101 to move the indicator 100, ratchet 102, and cluster gears 98 and 99 in a clockwise direction. As previously set forth, the diameter of the coin 69 determines the degree of counter-clockwise rotation of the reset lever 73. It will be apparent therefore that the diameter of the coin 69 also controls the height to which the cluster shaft 93 is raised.

In the event the diameter of the coin 69 is relatively small, such as a penny, the small tooth 109 on the ratchet 102 will engage the ratchet stop pawl 111 during clockwise rotation with the ratchet 102 to set the indicator 100 opposite the twelve minute mark on the dial 28. In the event the coin 69 is a nickel, the cluster shaft 93 will be raised sufficiently high that the small tooth 109 will clear or move above the stop pawl 111. However, the large tooth 110 is brought into position to engage the stop pawl 111, so that the indicator 100 will be moved to a point opposite the one hour indication on the dial 28.

When the reset lever 73 is released by the coin 69 and permitted to be rotated in a clockwise direction by the action of the spring 84, the cluster shaft 93 will obviously be lowered. During the initial downward movement of the shaft 93, the cluster time gear 98 engages the main time gear 37. Immediately subsequent to the engagement of the gears 98 and 37, the ratchet pawl 105 will contact a semi-circular extension 114 of the plate 24 and be disengaged from the ratchet gear teeth 109 to release the indicator 100. The main spring 82 through the medium of the main time gear 37 and timer 46 will then be permitted to drive the cluster time gear 98 and indicator 100 in a counter-clockwise direction. When the ratchet pawl 105 is disengaged from the ratchet gear 99, the ratchet 102 is immediately rotated counter-clockwise by the ac-

tion of the pawl spring 107 until the lower arm 104 contacts the upper surface (Fig. 2) of the stationary front plate 24. It will be readily seen that the stop pawl 111 will pivot about the pin 112 to permit movement of the small tooth 109 thereover during the counter-clockwise movement of the ratchet 102.

The warning flag mechanism, utilized to notify the operator when the parking time has expired, as well as when the meter is jammed, is illustrated in Figs. 11 and 12. The cluster shaft supporting lever 95 is provided with a raised cam surface 115 in downwardly spaced relation to the cluster shaft 93. The cam 115 is adapted to contact an actuating pin 116 carried by a flag actuating lever 117. The actuating lever 117 is pivotally supported on a pin 118 secured to the stationary rear plate 25 (see also Fig. 3). A semi-circular recess 119 is provided in the free end of the actuating lever 117 for purposes as will be hereinafter set forth. The warning flag 120 is pivotally supported on the pin 121 also secured (not shown) in the rear plate 25. A push pin 122 is provided on the flag 120 directly above the actuating lever 117 and in horizontally spaced relation to the pivot pin 121. The outer end 123 of the flag 120 is provided with a counterweight 124 suitable to facilitate the raising of the flag 120. The effective weight of the flag 120 on the opposite side of the pivot pin 121, however, remains greater than the effective weight on the end 123 thereof in order that the flag 120 will pivot by gravity to the zero or non-indicating position, as shown in Fig. 11.

As previously set forth, when the cluster shaft 93 is raised, the supporting lever 95 is pivoted clockwise (Fig. 11) about the pin 96. The cam 115 is thereby brought into contact with the actuating pin 116 to pivot the actuating lever 117 in a counter-clockwise direction about the pin 118. The free end of the lever 117 is therefore raised to contact the pin 122 and rotate the flag 120 in a clockwise direction into warning position as illustrated in Fig. 12. The recess 119 permits the lever 117 to move over the flag pivot pin 121 as illustrated in Fig. 12 to complete the upward movement of the flag 120. The flag 120 will then be visible through the sight glass 125 (Fig. 3) provided in the rear of the housing 15. When the cluster shaft 93 is again lowered upon release of the reset lever 73, the supporting lever 95 is pivoted counter-clockwise to disengage the cam 115 from the actuating pin 116. The actuating lever 117 is then permitted to pivot clockwise by gravity to free the flag actuating pin 122. The flag 120 will then obviously pivot counter-clockwise to a non-indicating position below the sight glass 125. It will thus be seen that each time a coin is inserted in the meter to actuate the reset lever 73, the warning flag 120 is momentarily raised, and in the event the reset lever 73 is jammed in a down position, the flag 120 will be retained in a raised position and be visible through the sight glass 125. When the reset lever 73 is jammed in a down position, the indicator 100, as previously set forth, will be set in such a position to indicate available parking time on the dial 26. However, the warning flag 120 will be simultaneously visible through the sight glass 125 to notify the operator and city officials that the meter is jammed and not operating correctly.

The actuating pin 116 (Figs. 3 and 11) extends beyond the supporting lever 95 and cam 115 into an arcuate slot 126 provided in the cluster time

gear 98. Assuming the time gear 98 is rotating in a clockwise direction (Fig. 12) when the parking time has expired, the trailing edge 127 of the slot 126 will contact the actuating pin 116 to pivot the actuating lever 117 in a counter-clockwise direction. It will thus be seen that the flag 120 will be pivoted into indicating position to notify the operator that the parking time has expired. When the indicator 100 is reset, as previously set forth, the cluster time gear 98 will be rotated in a counter-clockwise direction (Figs. 11 and 12) to the position shown in Fig. 11. The trailing end 127 of the slot 126 will thus be moved away from the actuating pin 116, permitting the actuating lever 117 to pivot in a clockwise direction and release the flag 120.

From the foregoing, it is apparent that the operator and the city officials will be notified through the medium of the warning flag 120 when the parking time has expired as well as when the meter 14 is not operating correctly.

Penny operation

Assuming the parking time has expired, the indicator 100 will be opposite the zero time marking on the dial 26 as illustrated in Fig. 1. When a penny 69 is inserted in the coin slot 16, the force of the operator's fingers through the medium of the penny will force the duck-bill 41 upwardly to the position shown in dotted lines in Fig. 1. The front and rear actuating levers 43 and 44 will be simultaneously rotated. The winding pawl 58 (Fig. 4) will rotate the main spring barrel 31 during rotation of the actuating lever 44 to simultaneously wind the main spring 32. Simultaneously, the cam surface 57 (Fig. 6) of the front actuating lever 43 will co-act with the push pin 58 to rotate the coin rotator 59 in a clockwise direction and bring the slotted extension 60 into coin receiving position as illustrated in dotted lines in Fig. 1 and full lines in Fig. 7. The shoulder 64 (Fig. 6) of the rotator pawl 62 will be simultaneously engaged with the actuating lever lock pin 65.

When the vertical center line (not shown) of the penny 69 passes inside of the lower end 72 of the duck-bill 41 (Fig. 1), then the duck-bill 41 will jump outwardly to the trailing edge of the penny 69 and permit the actuating levers 43 and 44 to rotate counter-clockwise. The coin rotator spring 68 through the medium of the coin rotator 59, the pawl 62, and the pin 65, will move the levers 43 and 44 downwardly to bring the duck-bill 41 into closed position, as illustrated in Fig. 1. The penny 69 will be forced inwardly by the duck-bill 41 into the slotted extension 60, and upon further counter-clockwise rotation of the coin rotator 59, the penny 69 will be brought into contact with the reset lever actuating pin 76.

Continued rotation of the rotator 59 will cause the penny 69 to move the reset pin 76 downwardly in the slot 21 to position "A" as illustrated in Fig. 2. In this position of the pin 76, the distance between the periphery of the coin rotator 59 and the pin 76 (due to the offset relation of the reset lever pivot point 74 and the coin rotator pivot point 29) will be slightly greater than the diameter of the penny 69. The pin 76 will therefore be released, permitting the reset spring 84 to move or return the reset lever 73 in a clockwise direction to the position as illustrated in Fig. 1. The coin rotator 59 will continue rotating in a counter-clockwise direction after the release of the pin 76 to carry the penny 69 downwardly along the coin chute 20 onto the lower end 82 of

the detent 68. The penny 69 will then be visible through a small sight glass (not shown) provided in the rear of the housing 15.

Simultaneously with the counter-clockwise rotation of the reset lever 73, the cluster shaft 93 will be moved upwardly by the link 81. During the upward movement of the shaft 93, the ratchet pawl 105 will first engage the ratchet gear 99 and then the cluster time gear 98 will be disengaged from the main time gear 37 to permit clockwise rotation of the reset cluster assembly by the spring 101. The penny tooth 109 of the ratchet 102 will contact the ratchet stop pawl 111 to stop the indicator 100 opposite the twelve minute marking on the dial 26, as illustrated in Fig. 2.

Also, simultaneously with the upward movement of the cluster shaft 93, the cam 115 (Fig. 11) will contact the actuating pin 118 to rotate the flag actuating lever 117 in a counter-clockwise direction. The free end of the actuating lever 117 will contact the pin 123 to raise the warning flag 120 to the position illustrated in Figs. 2 and 12.

When the pin 76 has been released at the "A" position, permitting the reset lever 73 to be released and returned to its starting position, the cluster shaft 93 is lowered through the medium of the link 81. During the downward movement of the shaft 93, the time gears 98 and 37 are first engaged and then the pawl 105 is disengaged from the ratchet gear 99 by the front plate extension 114 to place the clock works in operation. The ratchet 102 will immediately be turned counter-clockwise by the action of the pawl spring 107 to the position illustrated in Fig. 1. The main spring 32 through the medium of the main time gear 37 and the cluster time gear 98 will then gradually turn the indicator 100 counter-clockwise to a position opposite the zero marking on the dial 26. The speed of rotation of the main time gear 37 and hence the rate at which the parking time expires will be regulated by the timer 48 in the usual manner.

Nickel operation

Assuming again that the parking time has expired and the meter 14 is as illustrated in Fig. 1, upon insertion of a nickel (not shown) in the coin slot 19, the duck-bill 41 will be raised to a position slightly higher than that indicated by dotted lines in Fig. 1. The actuating levers 43 and 44 will be rotated as in the penny operation to wind the main spring 32 and move the coin rotator 59 into coin receiving position. When the nickel passes beneath the lower end 72 of the duck-bill 41, the levers 43 and 44 and the duck-bill 41 will be moved counter-clockwise by the action of the coin rotator spring 68 to the position illustrated in Fig. 1. The nickel will thereby be forced by the duck-bill 41 into the slotted extension 60 of the coin rotator 59 and be moved downwardly into contact with the reset lever actuating pin 76. Since the nickel has a greater diameter than a penny, the pin 76 will be moved downwardly in the slot 21 to position "B" indicated in Fig. 2. The sector arm 77 will simultaneously rotate the detent 68 in a clockwise direction, permitting a previously inserted coin (not shown) resting thereon to fall through the coin discharge slot 17 into a suitable coin box (not shown).

During the counter-clockwise rotation of the reset lever 73, the cluster shaft 93 will be raised as in the penny operation to engage the ratchet pawl 105 with the ratchet gear 99, and disengage

the time gears 98 and 37. The reset lever 73 is rotated counter-clockwise to a greater extent than in the penny operation however, thereby raising the cluster shaft 93 further than in the penny operation. The shaft 93 is raised to such an extent that the small tooth 109 moves above the ratchet stop pawl 111 as the indicator 100 is being set by the spring 101. The large tooth 113, however, will engage the stop pawl 111 to stop the indicator 100 opposite the one hour marking on the dial 26. When the pin 76 reaches the position "B," the pin is released, permitting the reset spring 84 to rotate the reset lever 73 in a clockwise direction back to the position illustrated in Fig. 1. As the reset lever 73 is returned in a clockwise direction, the cluster shaft 93 will again be lowered to engage the time gears 98 and 37 and disengage the ratchet pawl 105 from the ratchet gear 99. The warning flag 120 will be momentarily raised during the upward movement of the cluster shaft 93 as in the penny operation.

Cumulative indexing

For illustrative purposes only, it is assumed that a nickel (not shown) has been inserted previously in the meter 14 and remaining parking time, for example, forty minutes, is indicated as available. Upon insertion of another nickel (not shown) in the coin slot 19, the duck-bill 41 will be moved upwardly and the operation of the actuating levers 43 and 44, coin rotator 59, and reset lever 73 will be the same as stated above for the nickel operation. As previously set forth, during upward movement of the cluster shaft 93, the ratchet pawl 105 engages the ratchet gear 99 previous to the disengagement of the time gears 98 and 37. Therefore, the indicator 100 will be locked to the ratchet 102 and be retained opposite the forty minute marking on the dial 26 during disengagement of the time gears 98 and 37. It should also be noted that the ratchet 102 will be in the position illustrated in Fig. 1 when the new nickel is inserted in the meter. Thus, it will be seen that the ratchet 102 is turned clockwise during the resetting of the indicator 100 through the same arc as in the original nickel operation. The indicator 100 will therefore be moved through the same arc to increase the available parking time by one hour, thereby cumulating the parking time.

In the event a penny is inserted in the meter 14 when parking time is indicated as available, it will be readily seen that an additional twelve minutes will be added to the available parking time. A suitable stop (not shown) may be provided on the ratchet gear 99 to limit the maximum parking time that may be obtained to any desired limit—for example, two hours as shown.

One of the important features of the present meter is the compactness of construction. Referring to Fig. 3, it will be seen that the entire meter 14 may be installed in one sectional half portion of the meter housing 15. A meter mechanism similar to the mechanism 14 (not shown) may be readily placed in the opposite sectional half portion (not shown) of the housing 15 to provide what is commonly called a twin meter. The twin meter is usually installed between two parking spaces and is advantageous since only one supporting stand or pipe (not shown) is required.

From the foregoing, it is apparent that the present invention provides an automatic self-winding type selective coin operated parking

meter, wherein the clock works of the meter are caused to be wound by the force of the operator's fingers through the insertion of a coin in the meter. The meter will operate on more than one denomination of the coins, as well as multiple coins of each of the denominations. The extent to which the clock works is wound each time a coin is inserted in the meter may be varied as desired, by changing the position of a single winding pawl. The coin is moved through the meter by the energy of a spring to actuate the resetting and indicating mechanism. Furthermore, the meter cannot be jammed by the successive insertion of two or more coins and the resetting mechanism cannot be mischievously tripped to obtain free parking time. In addition, the meter mechanism is readily adapted for use as a single meter, or may utilize two mechanisms in the housing to provide for twin or double meter operation. The meter is obviously simple in construction as compared with like devices and may be easily repaired and adjusted.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. In a parking meter comprising a clock works, time indicating means adapted to be driven by said clock works for indicating the parking time utilized, clock winding means for winding said clock works, a coin inlet slot, a pair of actuating levers, a closure member carried by said actuating levers and normally extending into said coin inlet slot, said closure member responsive to a coin inserted in the inlet slot for movement out of said inlet slot with a simultaneous rotation of said actuating levers, means carried by one of said actuating levers for actuating said clock winding means upon rotation of said actuating lever, a spring loaded coin rotator adapted to move said coin through the meter, a push pin carried by said coin rotator cooperating with the other of said actuating levers to move said coin rotator into coin receiving position, and a reset lever actuated by said coin when moved by the coin rotator to reset said time indicating means.

2. In a coin controlled parking meter the combination of a clock works, time indicating means driven by said clock works for indicating the parking time utilized, a coin inlet slot, a spring loaded coin rotator for moving the coin through the meter, an actuating lever extending to a position opposite the coin inlet slot and adapted to be moved by the coin to move the coin rotator into coin receiving position, a reset lever for resetting said time indicating means, an actuating pin carried by said reset lever in the path of movement of a coin being moved through the meter by said coin rotator, said reset lever being pivotal about a point in spaced relation to the pivotal axis of said coin rotator, whereby upon simultaneous rotation of said coin rotator and said reset lever the distance between said reset lever actuating pin and said coin rotator is increased to provide for the passage of the coin beyond said actuating pin at a predetermined point.

3. In a parking meter comprising a clock

75

works, time indicating means driven by said clock works for indicating the parking time utilized, a coin inlet slot, an actuating lever extending into said coin inlet slot and responsive to a coin inserted in said slot for rotation away from the slot, means for moving the coin through the meter, a reset lever actuated by the coin moving through the meter for resetting said time indicating means, a lock pin carried by said reset lever, slot means in said actuating lever for receiving said lock pin upon rotation of said actuating lever to lock said reset lever in one position thereof, and cam means on said actuating lever adapted to be contacted by said lock pin upon rotation of said reset lever to preclude rotation of said actuating lever away from said coin slot.

4. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, means for moving the coin through the meter, a reset lever actuated by the coin moving through the meter for resetting said time indicating means, a lock pin carried by said reset lever, slot means in said actuating lever for receiving said lock pin when said coin slot is opened to lock said reset lever in one position thereof, and cam means on said actuating lever for contacting said lock pin upon movement of said reset lever to preclude movement of the closure member away from said coin slot.

5. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, a spring loaded coin rotator for moving the coin through the meter, a push pin carried by said coin rotator cooperating with said actuating lever upon rotation thereof to move said coin rotator into coin receiving position, a reset lever actuated by the coin when moved by said coin rotator for resetting said time indicating means, a lock pin carried by said reset lever, slot means in said actuating lever for receiving said lock pin when said coin slot is opened to lock said reset lever in one position thereof, and cam means on said actuating lever for contacting said lock pin upon rotation of said reset lever to preclude movement of the closure member from said coin slot.

6. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, means for moving the coin through the meter, a reset lever actuated by the coin moving through the meter for resetting said time indicating means, a lock pin carried by said reset lever, and slot means in said actuating lever for receiving said lock pin when said coin slot is opened to lock said reset lever in one position thereof.

7. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, means for moving the coin through the meter, a reset lever actuated by the coin moving through the meter for resetting said time indicating means, a lock pin carried by said reset lever, and cam means on said actuating lever for contacting said lock pin upon rotation of said reset lever to preclude movement of the closure member away from said coin slot.

8. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, means for moving the coin through the meter, a reset lever actuated by the coin moving through the meter for resetting said time indicating means, cooperating lock means on said actuating lever and said reset lever to preclude movement of said reset lever when said coin inlet slot is opened, and to lock said closure member in said coin slot upon movement of said reset lever.

9. In a parking meter comprising a clock works, a radially moveable reset cluster shaft, a cluster time gear assembly rotatably disposed on said reset cluster shaft and driven by said clock works, a time indicator carried by said time gear assembly for indicating the parking time utilized, a coin inlet slot, means for moving a coin through the meter, a reset lever connected to said reset cluster shaft and actuated by the coin moving through the meter in accordance with the denomination of the coin for moving said cluster shaft radially and disengaging said cluster time gear assembly from said clock works, ratchet means engaging said cluster time gear assembly during said radial movement of said reset cluster shaft previous to the disengagement of said cluster time gear assembly and said clock works, spring means for setting said time indicator upon disengagement of said cluster time gear assembly from said clock works, stop means engaging said ratchet means in accordance with the radial movement of said reset cluster shaft for setting said time indicator at a predetermined point according to the denomination of the coin, and spring means for returning said reset lever to normal position and engaging said cluster time gear assembly with said clock works.

10. In a parking meter comprising a clock works, a radially moveable reset cluster shaft, a cluster time gear assembly rotatably disposed on said reset cluster shaft and driven by said clock works, a time indicator carried by said time gear assembly for indicating the parking time utilized, a coin inlet slot, means for moving a coin through the meter, a reset lever connected to said reset cluster shaft and actuated by the coin moving through the meter in accordance with the denomination of the coin for moving said cluster shaft radially and disengaging said cluster time gear assembly from said clock works, a ratchet rotatably disposed on said cluster shaft and engaging said cluster time gear assembly during said radial movement of said reset cluster shaft previous to

the disengagement of said cluster time gear assembly and said clock works, variable sized teeth circumferentially spaced on said ratchet, spring means for setting said time indicator upon disengagement of said cluster time gear assembly from said clock works, a stop pawl selectively engaging said ratchet teeth in accordance with the radial movement of said cluster shaft for setting said time indicator at a predetermined point according to the denomination of the coin, spring means for returning said reset lever to normal position and engaging said cluster time gear assembly with said clock works, and stop means for disengaging said ratchet from said cluster time gear assembly upon engagement of said cluster time gear assembly with said clock works.

11. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, a spring loaded coin rotator for moving the coin through the meter, a push pin carried by said coin rotator cooperating with said actuating lever upon rotation thereof to move said coin rotator into coin receiving position, a reset lever actuated by the coin when moved by said coin rotator for resetting said time indicating means, and cooperating lock and pawl means carried by said actuating lever and said coin rotator to move said closure member into said coin slot prior to actuation of said reset lever.

12. In a parking meter comprising a clock works, time indicating means driven by said clock works for indicating the parking time utilized, a coin inlet slot, a pivotable actuating lever, a closure member carried by said actuating lever and normally closing said coin slot, said closure member responsive to a coin inserted in said coin slot for opening said slot and rotating said actuating lever, a spring loaded coin rotator for moving the coin through the meter, a push pin carried by said coin rotator cooperating with said actuating lever upon rotation thereof to move said coin rotator into coin receiving position, a reset lever actuated by the coin when moved by said coin rotator for resetting said time indicating means, a lock pin on said actuating lever, and a pawl carried by said coin rotator having a greater pivotal radius than said lock pin for engaging said lock pin when said coin rotator is moved into coin receiving position, whereby upon the release of said closure member by the coin said actuating lever is moved at a greater rotational speed than said coin rotator to move said closure member into said coin inlet slot prior to actuation of said reset lever.

13. In a coin controlled parking meter comprising a clock works, time indicating means driven by said clock works for indicating the parking time utilized, a coin inlet slot, a spring loaded coin rotator for moving the coin downwardly through the meter, an actuating lever extending to a position opposite the coin inlet slot and responsive to a coin inserted in said slot to move the coin rotator into coin receiving position, a reset lever for resetting said time indicating means, an actuating pin carried by said reset lever in the path of movement of a coin being moved through the meter by said coin rotator, the pivotal axis of said reset lever being below the pivotal axis of said coin rotator to provide a progressively increasing distance between said

actuating pin and said coin rotator during simultaneous rotation of said coin rotator and said reset lever, whereby said actuating pin is released at a predetermined point in accordance with the denomination of the coin.

14. In a parking meter comprising a clock works, a radially moveable cluster shaft, time indicating means carried by said cluster shaft and driven by said clock works for indicating the parking time utilized, a coin inlet slot, means for moving a coin through the meter, reset means actuated by the coin moving through the meter for moving said cluster shaft radially and resetting said time indicating means, a pivotable supporting lever for one end of said cluster shaft, a warning flag, and lever means interconnecting said supporting lever and said warning flag for actuating said warning flag upon radial movement of said cluster shaft in one direction, said lever means also being interconnected to said time indicating means to actuate said warning flag upon expiration of the parking time.

15. In a parking meter comprising a housing, a clock works in the housing, time indicating means driven by said clock works for indicating the parking time utilized, a coin inlet slot, an actuating lever, a closure member pivotally carried by said actuating lever and normally extending into said coin slot for closing said coin slot, stop means carried by said actuating lever precluding inward movement of said closure member relative to said actuating lever, whereby upon insertion of a coin in said coin slot said closure member is moved essentially vertically out of said coin slot to move said actuating lever in one direction, spring means for moving said actuating lever in a direction opposite to said first mentioned direction, whereby upon insertion of the coin beyond the end of said closure member normally disposed in said coin slot, said closure member is released and turned outwardly to a position along the outer edge of the coin to re-enter said coin slot, a shoulder in said housing for simultaneously turning said closure member to normal angular position during movement thereof into said coin slot whereby the coin is moved into the meter, and a reset lever actuated by the coin for resetting said time indicating means.

16. In a parking meter comprising a housing, a clock works in the housing, time indicating means driven by said clock works for indicating the parking time utilized, a coin inlet slot, an actuating lever, a closure member pivotally carried by said actuating lever and normally extending into said coin slot, stop means carried by said actuating lever precluding inward movement of said closure member relative to said actuating lever, whereby upon the insertion of a coin in said coin slot said closure member is moved essentially vertically out of said coin slot to move said actuating lever in one direction, a spring loaded coin rota-

tor for moving the coin through the meter, a push pin carried by said coin rotator and cooperating with said actuating lever to move said coin rotator into coin receiving position opposite said coin slot upon movement of said actuating lever in said one direction, a lock pin on said actuating lever, a pawl carried by said coin rotator and cooperating with said lock pin for moving said actuating lever in a direction opposite to said first mentioned direction, whereby upon insertion of the coin beyond the end of said closure member normally disposed in said coin slot, said closure member is released and turned outwardly to a position along the outer edge of the coin to re-enter said coin slot, a shoulder in said housing for simultaneously turning said closure member to normal angular position during movement thereof into said coin slot whereby the coin is forced into said coin rotator, and a reset lever actuated by the coin when moved by said coin rotator for resetting said time indicating means.

17. In a parking meter comprising a clock works, time indicating means adapted to be driven by said clock works for indicating the parking time utilized, clock winding means for winding said clock works, a coin inlet slot, a pair of actuating levers, a closure member carried by said actuating levers and normally extending into said coin inlet slot, said closure member responsive to a coin inserted in the inlet slot for movement out of said inlet slot with a simultaneous rotation of said actuating levers, means carried by one of said actuating levers for actuating said clock winding means upon rotation of said actuating lever, a coin rotator to move said coin through the meter, means cooperating between said coin rotator and the other of said actuating levers to move said coin rotator into coin receiving position upon movement of said other actuating lever, and a reset lever actuated by said coin when moved by the coin rotator to reset said time indicating means.
